US00D982572S

(12) **United States Design Patent** (10) **Patent No.:** **US D982,572 S**
Liu (45) **Date of Patent:** **** Apr. 4, 2023**

(54) **MOBILE PHONE HOLDER**

(71) Applicant: **Xiuxi Liu**, Guangdong (CN)
(72) Inventor: **Xiuxi Liu**, Guangdong (CN)
(73) Assignee: **DONGGUAN DONGDING ART & CRAFT CO., LTD**, Guangdong (CN)

(**) Term: **15 Years**

(21) Appl. No.: **29/766,163**

(22) Filed: **Jan. 14, 2021**

(30) **Foreign Application Priority Data**

(57) **CLAIM**

The ornamental design for a mobile phone holder, as shown.

DESCRIPTION

FIG. 1 is a front elevational view of a mobile phone holder showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof; and,

FIG. 9 is a third perspective view thereof.

1 Claim, 9 Drawing Sheets
